UNITED STATES PATENT OFFICE.

WILLIAM BRANDSTAEDTER, OF HANOVER, PENNSYLVANIA.

SAFETY DEVICE FOR BOX-ENDING MACHINES.

1,121,463.

Specification of Letters Patent. Patented Dec. 15, 1914.

Application filed October 8, 1913. Serial No. 794,093.

To all whom it may concern:

Be it known that I, WILLIAM BRANDSTAEDTER, a citizen of the United States, residing at Hanover, in the county of York and State 5 of Pennsylvania, have invented a new and useful Safety Device for Box-Ending Machines, of which the following is a specification.

My invention relates to paper box making 10 machines and the principal object of the same is to provide a simple safety attachment for protecting the operator's fingers against injury by the box making mechanism.

15 The invention is particularly designed for use in connection with box enders wherein the operator holds the paper box body on a former block while the former and the header are finishing the ends of the box. In such 20 instances the fingers of the operator hold the sides of the box to the side of the former block and the thumbs hold the bottom of the box to the front of the block and therefore the hands are necessarily exposed to the 25 danger of being caught between the former block and the header.

The object of the present invention is to prevent this by providing the former block 30 with guards that will prevent the fingers from being caught between the header and former block and which will push the fingers out of the way of danger.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

In the drawings:—Figure 1 is a front view broken away showing the safety attachment 45 in position. Fig. 2 is a side view of the former block showing the attachment. Fig. 3 is a top plan view of the former block, and Fig. 4 is a detail view of the safety device.

50 In the drawings I have only shown enough of the box making machine to properly illustrate the position and operation of the safety attachment and the letter A indicates the

header of usual construction, and B the former block of ordinary construction. Secured on each side of the former block are the plates or blocks 1 to which are secured the flat spring members 2 and to the opposite ends of the flat spring members are secured the safety devices or guards 3 which are provided on the ends with the right angle extensions 4. As is clearly shown in Figs. 2 and 4 of the drawings the guard members 3 are of such a shape that it extends upward from the flat spring members 2 and as shown in Fig. 2 engages the header A at all times.

Applicant is aware that it is not broadly new to provide a guard for a machine of this character but what he claims as new is a guard resiliently connected to the former block and held in such a position that it will engage the header at all times. It will be seen that it will be impossible to place the fingers between the header and former block as the guards 3 extend above the top of the former block and the right angle extension 4 will prevent the thumbs being placed in such position as to be caught between the header and former block. In machines of this character the former block reciprocates and moves toward the header. It will therefore be seen that when the former block is raised in my device the guard 3 will be forced downward and should the fingers be in any danger they will be pushed downward with the guard.

Having thus described the invention, what I claim as new and desire to secure by Letters Patent is:—

In a forming machine, the combination 90 with a header, and a movable former block, of finger guards yieldably connected to the sides of the block at a point below the upper edge of the block and extending upwardly at an angle so that the free ends extend 95 above the top of the block, and said finger guards having extensions extending in front of the block.

In testimony that I claim the foregoing as my own, I have hereto affixed my signature in the presence of two witnesses.

WILLIAM BRANDSTAEDTER.
